WELL SWAB

Jerome M. Donzis, San Antonio, Tex.

Application December 12, 1949, Serial No. 132,525

6 Claims. (Cl. 103—225)

1

This invention comprises novel and useful improvements in a well swab and more specifically pertains to a swabbing device incorporating therein safety features in the form of an overload release, whereby an overloaded swab will then uncover a bypass passage therethrough to prevent breakage of the swab operating cable or its operating mechanism.

The primary object of this invention is to provide an improved well swab of a simplified, improved and durable construction which will incorporate automatic overload releasing features therein for preventing breakage of the operating cable and operating mechanism thereof.

A further object of the invention is to provide an overload releasing well swab which is provided with a check valve assembly for permitting the swab to pass through liquid during its insertion into a well casing, and to trap the liquid upon its upward movement; together with resilient means responding to an overload for withdrawing the entire valve assembly to uncover a by-pass passage through the swab itself and permit release of the overload through the swab.

These, together with various ancillary features and objects of the invention which will later become apparent as the following description proceeds, are attained by the present invention, a preferred embodiment of which has been illustrated by way of example only in the accompanying drawings, wherein:

Figure 1 is a vertical longitudinal sectional view through a portion of a well casing or tubing showing the improved well swab forming the subject of this invention positioned therein;

Figure 2 is a vertical central longitudinal sectional view through the improved well swab showing the same in position in a well casing or tubing;

Figure 3 is a view similar to Figure 2 but showing the swab in its overload release position;

Figure 4 is a horizontal sectional view taken substantially upon the plane of the section line 4—4 of Figure 2; and

Figure 5 is a side elevational view of the swab, cage, and valve assembly forming the subject of this invention.

Referring now more specifically to the accompanying drawings, wherein like numerals designate similar parts throughout the various views, it will be seen that the numeral 10 designates a well casing or tubing of any desired type which is shown as extended through a formation or strata 12 into a well hole 14 in the bottom thereof. As shown in Figures 1-3, the improved

2

well swab forming the subject of this invention is shown positioned in such a casing or tubing to perform its well swabbing or cleansing action in accordance with conventional practice. The improved well swab consists of a hollow body 16 of any desired shape and size, but which preferably comprises a sleeve which is open at its upper and lower ends, but has a partition 18 intermediate these ends.

10. This partition, which is apertured at its center, thus divides the interior of the body 16 into an upper chamber 20 which is closed by an internally threaded cap member 22 likewise centrally apertured; and a lower chamber 24 which is internally threaded to receive the externally threaded neck portion 26 of a swab head 28 of any conventional design. However, in accordance with this invention, an axial bore or passage 30 extends through this swab head and into the interior of the chamber 20.

At a convenient point adjacent the lower ends of the lower end of the body 16, a plurality of longitudinally extending slots 32 are provided establishing communication between the interior 25 of the body and the exterior thereof, thus providing communication between the interior of the well casing or tubing 10 and the interior of the body of the swab.

Slidably inserted in the open lower end of the chamber 24 and slidable within the same is an inner cage 34 which is likewise provided with longitudinally extending slots 36 which are co-extensive with and thus register with the slots 32 in the body member 16. The cage is further provided with an annular internal flange or shoulder 38, to the under side of which is adapted to be clamped the external flange or shoulder 40 of a sleeve 42 constituting a valve seat. The lower surface of this flange 40 being retained as by an internally flanged tubular sleeve or member 44, threadedly engages the internally threaded lower portion of the cage 34.

The upper surface of the valve assembly 42 constitutes a spherical seat for receiving a spherical or ball valve 46 constituting a check valve, this valve being retained within the hollow inner cage 34 and being freely movable therein.

Disposed in the upper portion of the bore 24 and seated between the partition 18 therein and the upper surface of the inner cage 34 is a compression spring 48 which serves to urge the inner cage to its lowermost position, that being the position shown in Figure 2, wherein the slots 36 of the inner cage are in complete and full registry with the slots 32 of the body 16. In this position,

a by-pass passage is established around the swab head 28, this passage consisting of the registering slots 32 and 36, the passage through the valve member 42 which is controlled by the ball valve 46, and the passage 26 extending through the swab head.

Swabbing rod 50, which may comprise a rigid rod, is receivable and slidable in the apertures in the upper closure cap 22, and the partition 18, having its lower end threaded, as at 52, for engagement rigidly in the upper portion of the inner cage 34. This rod 50 may be secured to a swabbing cable, or may be directly connected to any suitable operating mechanism whereby the same may be lowered into and removed from the well for imparting a vertical reciprocating movement to the swab head 28 for cleansing or swabbing the interior of the well casing or tubing 10.

The upper compartment or chamber 20 within the body 16 receives a steel or similar sleeve 54 having an axial bore therethrough for guidingly and slidably receiving the rod 50 therein. This sleeve constitutes a sealing means for preventing the ingress of foreign matter into the interior of the body 16 where the same might damage the bearing connection of the sliding rod 50 with the aperture through the partition 18 and might impede operation of the spring 48 in the chamber 24.

As shown in Figure 5, the inner cage 34 is provided with an elongated guide slot 56 which is adapted to receive the end of a set screw 58 or the like, which, as shown in Figure 1, extends through the body 16 and into the slot 56 to constitute a key or guide for the same and thus prevent rotation of the cage 34 within the body, and thus assure registry of the slots 32 and 36.

From the foregoing, the operation of the device will now be readily understood. When the parts are arranged as in Figure 2, the spring 48 has urged the inner cage 34 to its lowered position, so that the slots 32 and 36 are in complete registry. When, now, the swabbing rod 50 with the swab assembly secured thereto is lowered, as shown by the arrow in Figure 2, the swab 28 moving downwardly in the casing 10 will encounter the surface of liquid therein, whereupon the liquid will flow upwardly through the passage 30, will lift the ball valve 46 from its seat, as shown in dotted lines in Figure 2, and the liquid will flow as indicated by the arrows through the by-pass passage by means of the passages 30, 32, and 36 to the space above the swab head. After the swab has completed its downward stroke, the ball valve 46 will seat by its own weight, thus trapping the fluid disposed above the swab head 28, which, in accordance with conventional practice, will establish a fluid-tight seal with the walls of the casing or tubing 10 over which the swab head travels. When the swabbing rod 50 is raised, its engagement with the inner cage 34 will raise the same, and through the spring 48 and partition 18 will raise the entire body 16 and the swabbing head 28 rigidly attached thereto. If, however, too great a weight of liquid has been trapped above the swabbing head 28, so that the strength of the swabbing device is threatened thereby, the weight of this trapped liquid will cause the compression spring 48 to yield, until the position shown in Figure 3 is attained, at which time this compression spring is compressed, the inner cage has moved upwardly within the body 16 so that the lower end of the same including the valve seat assembly has completely uncovered the slots 32, permitting the fluid trapped

above the swab head to pass through the by-pass passage, as indicated in arrows in Figure 3. When a sufficient weight of fluid has been released, so that the spring 48 is now capable of lifting the body 16 and the swab head 28 to the normal position shown in Figure 2, the by-pass passage will then be closed and the swabbing operation may be continued.

From the foregoing, it will be seen that there is provided a swabbing assembly which automatically accommodates itself to overloads and yields to permit discharge of the excess portion of the load imposed upon the swab and this, without any further attention upon the part of the operator, thus minimizing damage and losses due to breakage of the swab, the swabbing rod or the operating mechanism of the same.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. A well swab comprising a body, an inner cage slidable in said body, a swabbing rod supporting said inner cage, resilient means yieldingly supporting said body on said inner cage, a swab head secured to the lower end of the body, a liquid passage through said swab head and body, a non-return valve assembly in said inner cage controlling said passage, said inner cage and body having registering slots forming part of said passage, said inner cage being slidable upon predetermined loads upon said swab to uncover the slots in said body whereby free communication through said passage to both sides of said swab is established.
2. A well swab comprising a body, an inner cage slidable in said body, a swabbing rod supporting said inner cage, resilient means yieldingly supporting said body on said inner cage, a swab head secured to the lower end of the body, a liquid passage through said swab head and body, a non-return valve assembly in said inner cage controlling said passage, said inner cage and body having registering slots forming part of said passage, said body and cage having cooperating guide means to prevent relative rotation.
3. A well swab comprising a body, an inner cage slidable in said body, a swabbing rod supporting said inner cage, resilient means yieldingly supporting said body on said inner cage, a swab head secured to the lower end of the body, a liquid passage through said swab head and body, a non-return valve assembly in said inner cage controlling said passage, said inner cage and body having registering slots forming part of said passage, said body comprising a sleeve, a partition dividing said body into upper and lower chambers, said inner cage being slidable in said lower chamber.
4. A well swab comprising a body, an inner cage slidable in said body, a swabbing rod supporting said inner cage, resilient means yieldingly supporting said body on said inner cage, a swab head secured to the lower end of the body, a liquid passage through said swab head and body, a non-return valve assembly in said inner cage con-

trolling said passage, said inner cage and body having registering slots forming part of said passage, said body comprising a sleeve, a partition dividing said body into upper and lower chambers, said inner cage being slidable in said lower chamber, a packing member in said upper chamber guidingly receiving said swabbing rod.

5. A well swab comprising a body, an inner cage slidable in said body, a swabbing rod supporting said inner cage, resilient means yieldingly supporting said body on said inner cage, a swab head secured to the lower end of the body, a liquid passage through said swab head and body, a non-return valve assembly in said inner cage controlling said passage, said inner cage and body having registering slots forming part of said passage, said cage having an internal shoulder, said valve assembly having an external shoulder engaging said internal shoulder and retaining means securing said shoulders together.

6. A well swab comprising a body, an inner cage slidable in said body, a swabbing rod supporting

said inner cage, resilient means yieldingly supporting said body on said inner cage, a swab head secured to the lower end of the body, a liquid passage through said swab head and body, a non-return valve assembly in said inner cage controlling said passage, said inner cage and body having registering slots forming part of said passage, said cage having an internal shoulder, said valve assembly having an external shoulder engaging said internal shoulder and retaining means securing said shoulders together, the upper end of said valve assembly forming a valve seat.
